GRADING MACHINE

Joseph B. Smith, Havana, Ill.

Application December 3, 1937, Serial No. 177,940

7 Claims. (Cl. 37—178)

This invention relates to improvements in road graders.

Said invention has for one of its objects the production of a simple form of road grader of comparatively light weight whereby it can be supported and carried by any type of tractor, from a position on which the operator may easily raise and lower the scraper blade or make various adjustments according to requirements.

Another object is to construct a type of road grader of simple form but with advantages not resident in known approved forms of grading machines, and which will require but a single operator for its manipulation.

Again, an object lies in providing a novel arrangement for raising and lowering the extremities of the scraper blade, including a skid member to act for preventing sidewise or lateral shifting movement of the grader while at work.

Still another object is that of so constructing a grader that the scraper blade may be very easily and quickly adjusted with exactness to any angle required for any given piece of work.

Other advantages will be pointed out in the following specification aided by the appended drawings forming part hereof wherein:

Figure 1 is a plan of a grading machine constructed according to my invention.

Figure 1^a is a side elevation in detail and in part section, of certain parts entering into the invention.

Figure 2 is a transverse sectional elevation of a skid member shown in Figure 1.

Figure 3 is a side elevation of the skid member and mechanism for control thereof.

Figure 4 is a side elevation of the grading machine shown in Figure 1.

Figure 5 is a transverse section of a support for a scraper blade, not shown, and part of mechanism for use in tilting said support.

Figure 6 is a side elevation, on a larger scale, of a hanger member shown in Figure 4, and

Figure 7 is a front elevation of a guide member also shown in Figure 4.

In said drawings part of a tractor platform is indicated at 1 to a rod 2 of which, for example, is attached for vertical swinging movement a pair of drag members or bars 3 which extend rearwardly from said platform. Each of said bars 3 forms a part of a separate braced frame structure including an upright member 4 and a diagonal member 5 connecting said member 4 to said bar 3, the two frame structures rising and falling independently.

As best shown in Figure 4 a hand lever 6 with

any usual latch arrangement 7, together with a notched sector 8, is mounted on the tractor platform 1, a rock-shaft 9 operated by the lever having a pair of upstanding levers 10, the levers lying forward of a pulley 11 mounted on the upper portion of each of the members 4. Attached at one end to each lever 10 is a cable 12 which passes around a pulley 11, the other end of said cable being suitably attached to any fixed part on the tractor platform but not necessary to describe in detail.

It is to be noted that in a swing of the hand lever 6 toward the position shown in broken lines the cable will draw upon the frame structure 3, 4, 5 and lift or swing the same upon the rod 2 as a pivot.

Slidable upon each of the members or bars 3 is a hanger which in this instance comprises a head 13 to slidably receive the bar and having a depending leg 14, the extremity of the latter being loosely connected in any suitable manner with an angle bar 15 supporting a scraper blade 16. In the present instance the leg 14 may receive a bolt 14' loosely extending through a hole in said angle bar, the head of which bolt serving to prevent separation of said leg from the latter.

The bar 3 has a series of holes 17 spaced along the same, a pin 18 being adapted to secure the head in any position on said bar, it being observed, that the head 13 at the right as seen in Figure 1, since adjusted forward of the position of the other head, at the left, serves to hold the right end of the scraper blade in advance of the other.

In thus changing the angle of the blade in moving an end thereof in a forward or rearward direction the bars 3 which are loosely hung at one of their ends on the rod 2 permit the hangers 13—14 to swing to and from each other, this being permitted, also, due to the loose connection of such hangers in the angle bar 15.

Since the angle bar 15 swivels on the two hangers it is free to tilt laterally endwise as well as to rock. In rocking the cutting edge of the scraper blade 16 may be presented at various angles with respect to the ground surface. This rocking is brought about by raising and lowering the thread bars 30 by means of the hand wheels 31. That is to say, since the skids 26 are supported at their rear ends upon the road surface those ends act as their fulcrums. If a thread bar of a given skid is raised the forward end of that skid will lift the blade 16 through the instrumentality of the brackets 29. Stated in another way, when a thread bar is operated to lift a skid at its

pivoted end the blade-end adjacent thereto is raised while the trailing edge of that skid rests upon or is dragging upon the road surface.

To the end that this angular adjustment may

- 5 be had the short arm of a bent lever 19 extends through a bracket 20 secured to the angle bar 15 midway the length thereof, Figure 1, said bracket being permitted to swing about the lever-end. Any means of providing for this free action, 10 may be used while preventing the separation of the bracket and lever. In this instance a nut 21 may be screwed upon the lever-end beneath the bracket wall while the extremity of the lever may lie in a tubular boss 22 of said bracket. The 15 long arm of the lever extends forward within an upstanding yoke member 23, Figure 7, mounted on a bar 24, said yoke-member having spaced holes throughout its height for receiving a pin 25, said pin serving to hold the lever in any position in which it may be placed, and yet the long arm of the lever 16 may rotate in any lateral tilt of the scraper blade.

Near each end of the angle bar 15 is a member which I shall term a "skid" denoted at 26 to trail the scraper blade 16. This member may be wide and of some considerable length, being provided with a flange 27 at each of its side edges paralleling each other and disposed at right angles to the longest measurement of the scraper blade 16. The forward end of the skid is pivoted to the lower edge of the angle bar 15 substantially as shown in Figures 2 and 3, a rod 28, for example, passing through the flanges 27, and through brackets 29 fixed on said angle bar, but 30 one of which brackets is shown. Extending through a slot 26' in the skid near its pivoted end is a thread bar 30, this likewise extending through the upper member of said angle bar 15 and provided with a hand wheel 31 threaded upon said 35 thread bar.

In order to adjust and fix the skid with respect to the scraper blade some such means as the following may be used.

The thread bar may extend through a member 40 of two parts 15' affixed in suitable manner to the angle bar 15, said parts as shown in Figure 1^a each having a flange 15² to engage about a flange 31' of the hub of said wheel. By this means or any equivalent thereof it is clear that the thread bar if non-rotatable, will be raised or lowered 45 with respect to the angle bar according to the direction of wheel rotation and thus the skid is positively operated upon and remains fixed at any position with respect to the scraper blade. 50 The lower end of the thread bar is suitably pivoted to the skid on lugs 32, for example, by means of a pin 33 by which means the said thread bar is held from rotating, the wheel 31 rotating with 55 respect thereto to bring about the action named.

60 By rotating the said wheel the rear portion of the skid is raised or lowered with respect to the cutting edge of the scraper blade 16.

In service the bars 3 act as the draft elements, 65 the scraper blade being drawn by means of the two hangers 13, 14 and the angle bar 15. As stated, the adjustment of the hangers along the bars 3 serve to adjust the blade at any angle to the line of advance. Due to the fact that the side flanges 27 of the skids 26 can cut into the 70 ground they serve to prevent any side shift of the machine in the angular attack of the scraper blade upon the work. The skids thus serve much the same as the familiar "landside" of a plow.

75 The scraper blade may be adjusted to any height desired above the road surface by means

of the lever 6 so that a given depth of gravel or other surfacing material may be spread and at this time the skids may be adjusted to assist in supporting the blade at any such given height.

The hand wheels previously referred to since 5 held by their flanged hubs within the parts 15' serve, when turned, to lift the skids 27, or to depress them, through the thread-bars 30. Through this instrumentality either end of the scraper may be raised or lowered to give it the 10 lateral tilt desired. In attempts to depress the skid through the hand wheel and thread bar the rear or trailing end of the skid will resist lowering in bearing upon the road-surface, naturally causing lifting of the blade at that end carrying it. 15 In this way either end of the blade can be raised and there maintained. Since the skids are, in effect, fixed with respect to said blade in any position of adjustment. Any such action is independent of and without respect to the lifting 20 parts 4, 6, 11 and, of course, not hindered by such parts.

While I have shown and described the parts 3, 4, 5 as two separate frame structures they may be parts of a single structure to be raised 25 and lowered as a unit by means of the lever 6, there being sufficient looseness or "play" between the legs 14 of the hangers 13, and the angle bar 15, to permit lateral tilt of the scraper blade 30 in the vertical adjustments of the skids 26 to adjust said blade for any angle of such tilt with respect to a horizontal line.

I claim:

1. A grading machine including in its construction, and in combination, a support constituting a draft device, a rearwardly extending frame-structure pivoted to said support, mechanism on the support engaging with and adapted for imparting vertical swinging movement to said frame structure, a member including a scraper-blade, a lever-arm carried by the frame structure and operatively connected to the member at its middle length, means for fixing the lever-arm at a given elevation while permitting lateral tilt of said member and its blade, a pair of hangers carried by the structure loosely connected to the member and spaced from each other and spaced at opposite sides of the connection of said lever-arm with said member, a skid pivotally attached to each extremity of the member, and means at each skid to adjust it with respect to said member for imparting vertical movement to the same and said blade.

2. A machine for the purposes named including in combination with a support constituting a draft device, a frame structure pivoted to said support and extending rearward therefrom including fixed spaced uprights at its rear, mechanism on said support engageable with the frame structure for imparting vertical swinging movement thereto, a member suspended from the structure including a scraper-blade, a lever-arm operatively connected to the member at its middle length, means to fix the lever-arm at a given elevation while permitting lateral tilt of the member and its blade, and a pair of hangers carried by the structure loosely connected to the member and spaced from each other and spaced at opposite sides of the connection of said lever-arm with said member.

3. A machine for the purpose named including in combination with a support constituting a draft device, a frame structure pivoted to said support and extending rearward therefrom including fixed spaced uprights at its rear, mecha- 70 75

nism on said support engageable with the frame structure for imparting vertical swinging movement thereto, a member suspended from the structure including a scraper-blade, a lever-arm operatively connected to the member at its middle length, means to fix the lever-arm at a given elevation while permitting lateral tilt of the member and its blade, a pair of hangers carried by the structure loosely connected to the member 5 and spaced one at each side of the connection of said lever-arm with said member, a skid attached to each extremity of the member, and means at each skid to vertically adjust it with respect to the latter for adjusting it and the scraper-blade 10 in a vertical direction.

4. A machine for the purpose named including in combination with a support constituting a draft device, a frame structure pivoted to said support and extending rearwardly therefrom including fixed spaced uprights at its rear, mechanism on said support engageable with the frame structure for imparting vertical swinging movement thereto, a member suspended from said structure including a scraper-blade, a lever-arm 15 operatively connected to the member at its middle length, means to fix the lever-arm at a given elevation while permitting lateral tilt of the member and its blade, said member adapted to rotate in a horizontal plane on said lever-arm, a pair 20 of hangers carried by the structure loosely connected to the member spaced one at each side of the connection of the lever-arm with said member, a skid attached to each extremity of the member, and means at each skid to vertically 25

30

adjust it with respect to the latter for moving it and the scraper-blade in a vertical direction.

5. The invention according to claim 4 including means to secure the hangers in given adjustments upon said structure. 5

6. The invention according to claim 4 including the adjustability of the hangers along the frame structure in the line of advance of the machine. 10

7. A grading machine including in its construction, and in combination, a support constituting a draft device, a rearwardly extending frame-structure pivoted to said support, mechanism on the support engaging with and adapted for imparting vertical swinging movement to the frame-structure, a member including a scraper-blade, a lever-arm carried by the frame-structure and operatively connected to the member at its middle length, means for fixing the lever-arm at a given elevation while permitting lateral tilt 15 of said member and its blade, a pair of hangers carried by the frame-structure and loosely connected to the member, said hangers being spaced apart one at each side of the place of connection of the member and lever-arm, a skid pivotally 20 attached at one end to each extremity of the member and extending rearwardly therefrom, an upstanding thread-bar pivotally carried at one end on the skid between the extremities thereof, and a hand wheel having threaded engagement 25 with the thread-bar, said wheel being free to rotate but otherwise held with respect to the member. 30

JOSEPH B. SMITH.
